RONALD McNAB, OF ASNIÈRES, FRANCE, ASSIGNOR TO REMINGTON TYPEWRITER COMPANY, OF ILION, NEW YORK, A CORPORATION OF NEW YORK.

COMBINED TYPE-WRITING AND COMPUTING MACHINE.

1,250,477.

Specification of Letters Patent. Patented Dec. 18, 1917.

Application filed June 9, 1914. Serial No. 843,963.

To all whom it may concern:

Be it known that I, RONALD McNAB, British subject, and resident of Asnières, Seine, France, have invented certain new and useful Improvements in Combined Type-Writing and Computing Machines, of which the following is a specification.

My invention relates to writing and computing machines, and it has for its principal object to provide improved means whereby numbers written in a plurality of columns can be registered on a single register. In the specific form of the invention shown in the drawings, I have provided means whereby the Wahl adding machine can, by the addition of a simple and inexpensive attachment, be adapted for cross-footing, though it will of course be understood that my invention is applicable or readily adaptable to other adding machines than the one mentioned.

To the above and other ends my invention consists in certain features of construction and combinations and arrangements of parts, all of which will be fully set forth herein and particularly pointed out in the claims.

One embodiment of my invention is illustrated in the accompanying drawings, in which—

Figure 1 is a side elevation, partly in section, of so much of a Remington-Wahl type-writing and computing machine as is necessary to illustrate the embodiment of my invention therein.

Fig. 2 is a front elevation of the same.

Fig. 3 is an enlarged detail view in fore and aft vertical section through a certain stop device.

The main frame of the Remington No. 11 typewriter comprises a base part 1, corner posts 2 and a top plate 3 on which last are supported the stationary rails 4 for the truck 5 of the typewriter carriage in which is mounted the platen 6. Said carriage is drawn across the machine by a spring drum 7 and strap 8, which strap is connected with a bracket 9 of the carriage truck 5. Said truck has hinged thereto at 10 a feed rack 11 which meshes with a feed pinion 12 on the front end of a shaft, which shaft at its rear end has a duplex escapement wheel 13 mounted thereon for cooperation with a dog

14 mounted on a dog rocker 15, which dog rocker is operated by a link 16 connected with a universal bar, not shown.

The typewriter usually includes printing keys for printing any words and numbers and various characters, the numeral keys 17 being the only ones shown. These are mounted on key levers 18 connected with type bars 20 by links 21, sub-levers 22 and links 23. Said type bars are pivoted on a type bar segment 24 and carry types adapted to strike against the front face of the platen 6.

Tabulator mechanism is provided for the usual purposes of such mechanism, including that of writing numbers in columns. This mechanism, as shown in the present instance, comprises denominational push keys 25 mounted on the forward ends of push rods 26, which near their forward ends, pass through a guide 27 and have restoring springs 28 connected therewith. Each of the push rods 26 at its rear end is pivoted to the lower end of a lever 30, all of said levers being pivoted at 31 in a frame 32, and each of them having its upper end 33 constituting a denominational stop for cooperation with one or any suitable number 34 of column stops 35, which column stops are mounted on a transverse toothed rack bar 36 supported by brackets 37 from the carriage truck 5.

In order to release the carriage when any of the tabulator keys is operated, each of the push rods 26 has fixed thereon a collar 37, which collar, when the key is operated, is adapted to move toward the rear a transverse universal bar 38 mounted on a rock shaft 40 by means of arms 41 depending from said rock shaft. Each of said arms 41 is connected by means of a push link 42 with an arm 43 extending downward from a rock shaft 44 to which it is fixed. Said rock shaft 44 has also fixed thereon an arm 45 to which is connected a restoring spring 46. Said rock shaft also has fixed thereon an arm 47 which is connected by a link 48 with a release lever 49 pivoted at 50 to a bracket 51 mounted on the top plate 3, and having its forward end formed into a shoe that underlies the feed rack 11. The construction is such that whenever any tabulator key is operated said feed rack is lifted out of engagement with the pinion 12 and the car-

riage is thus released from its escapement mechanism and is left free to run until arrested by the tabulator stops.

The Wahl adding attachment comprises 5 a stationary frame piece or support 51 which is mounted on the top plate 3 of the typewriter by means of two brackets 52 to which said frame piece 51 is secured by screws or bolts 53 (Fig. 2), said bolts passing through perforations in the brackets 52 and being secured in place by nuts 54. An actuator 55 is mounted on the lower part of the frame piece 51 or, rather, said frame piece constitutes a part of the stationary 10 framework of the actuator. It is not deemed necessary to go into a description of said actuator further than to say that it includes certain mechanism operated by links 56 extending upward from the key levers 18 of 15 the numeral keys and connected at their upper ends with levers 57 of the actuator. One of the effects of the depression of one of the numeral keys, and with it one of the links 56, is to cause an oscillation of a rock 20 shaft 58 and a partial rotation of a master wheel 60. The carriage truck 61 of the Wahl adder consists essentially of a bar extending across the front of the machine and having its upper and lower parts formed into suitable 25 trackways for coöperation with anti-friction wheels or rollers 62 journaled in various ways on the frame piece 51 at the middle of the machine; and the ends of said truck are supported and propelled by means 30 of arms 63 extending to the right and left, respectively, of said truck and having slots 64 therein for coöperation with screws 65 threaded into the forward ends of arms 66 rigidly mounted, as by screws 67, on the carriage 35 truck 5 of the typewriter.

The forward part of the carriage bar 61 is formed with a dove-tail cross section as shown at 68 and on this dove-tail there is 40 adjustably mounted an adding head 70 of the ordinary Wahl type. This adding head, register or totalizer is provided with a hand-operated latch 71 adapted to coöperate with teeth 72 in the upper edge of a rack bar 73 secured to the forward face of the carriage 45 bar 61. The teeth 72 are spaced apart in conformity to the letter spacing of the typewriter and the construction is such that the totalizer can be set along the carriage to any desired letter space position and there 50 secured, and it can be moved along the carriage by hand and set to some new letter space position by first depressing the finger piece or latch 71.

The mechanism thus far described is or 55 may be that of the Remington-Wahl typewriting and computing machine, as heretofore constructed.

In the form of my invention shown in the drawings I mount upon the computer 60 carriage 61 a rack bar 74 having vertical

slots cut in its front and rear edges a letter space distance apart, said bar, as here shown, being constructed in substantially the same way as the column stop bar of a Gorin tabulator, such, for example, as the bar 35. Said bar 74 is mounted at its ends on brackets 75 secured by screws 76 to the carriage 6. The bar 74 is fastened to the brackets 75 by means of screws 77 passing through slots 78 in the brackets 75, said slots being provided 75 in order to permit of the necessary adjustment of the bar lengthwise of the carriage. The bar 74 is located above the truck 61. On said bar I mount one or more stop devices 80 of a construction which will be understood from Fig. 3. Each of these devices comprises a plate-like part with a notch or open slot therein adapted to fit over the bar 74 as shown in Fig. 3, and into a pair of notches or slots formed in the 80 front and rear edges of said bar, after the general fashion of the adjustable column stops of the Gorin tabulator, and after the general fashion of the stops 34 shown in the present instance, except that the devices 80 are here shown as being set on from the top of the bar 74 instead of being pushed on from the rear as the stops 34 are represented as being. The forward part of the device 80 has a hole 81 extending vertically 85 through it, said hole being reduced near the bottom to form an annular shoulder. A pin 82 has its upper end of a size adapted to play up and down in the large part of the hole 81 and its lower reduced part adapted to move up and down in the reduced part of said hole, and a light spring 83 is coiled about the reduced stem of the pin 82 and compressed between the shoulder in the lower part of the hole and the shoulder 90 formed by the enlarged part of the pin. The motion of said pin under the influence of said spring is limited by a collar 84 fixed on the lower extremity of said pin where it projects below the device 80. This collar 95 100 constitutes a sort of an enlargement of the lower end of the pin and it also constitutes a stop for the totalizer 70, as will presently be seen. The spring 83 normally holds the stop 84 at an elevation such as to allow the totalizer 70 to move freely underneath said stop so that under normal conditions the stop or stops 84 would not interfere with the totalizer being adjusted from one end of the carriage to the other. Said stops are, 105 however, adapted to be depressed into the path of the upper part of the totalizer. Any desired one of these stops can be pressed 110 down to operative position by hand, and in case that mode of operation is adopted, 115 cross-footing can be done with the device already described. I prefer, however, to depress the stops automatically as an incident to some other operation. In the mechanism shown in the drawings, these stops are de- 120 125 130

pressed upon the operation of a tabulator key. To this end a depressor 85 is mounted on the upper end of a stiff rod 86 which can be suitably guided for up and down motion in any convenient way. As here shown it passes through a bracket 87 which consists of a piece of sheet metal having a perforation through which the right-hand one of the bolts 53 passes and the bracket is secured to the rear face of the right-hand bracket 52 by means of the nut 54, and having its left-hand end bent around the rod 86. At its lower end said rod is pivoted at 88 to a lever arm 90 which is rigidly mounted on the same hub 91 (Fig. 2) as the right-hand one of the arms 41. The primary purpose of this arm 90 in the Remington machine is to operate the key-lock forming part of the line-lock mechanism. Said arm 90 is arranged to depress a flat spring arm 92 which is secured upon the upper edge of a sheet metal bar 93 which at its ends is integral with arms 94 pivoted in the base 1 of the machine on pivot pins 95. The lower edge of this line locking bar 93 is bent toward the rear to constitute a flange 96 adapted to coöperate with undercut brackets 97 on the printing key levers to lock the same whenever one of the tabulating keys is operated. This line locking bar 93 is also adapted to be operated by the typewriter carriage at the end of a line of writing through certain intermediate mechanism, none of which is shown except the lower end 35 of a link 98, which link is connected with one of the lever arms 94. The construction is such that when one of the tabulator keys is operated and the arm 90 is thereby moved downward, the rod or bar 86 is also moved downward, depressing the member 85 to the 40 position shown in dotted lines in Fig. 2. This member at its two ends is formed with bevels 100. The construction is such that when the carriage moves at a time when one 45 of the tabulator keys is pushed in, then any of the pins 82 that moves under the device 85 will be depressed, as shown in dotted lines in Fig. 2, bringing the part 84 into position to arrest the totalizer 70. The depressor 85 will be restored to normal position by the spring 46, but an additional spring acting more directly on said depressor, can be added if desired.

The two extreme positions of the totalizer 55 on the carriage can, if desired, be defined by another form of stop which does not require to be depressed, and I have shown two such stops 101. These are of the sort that are already in use on the Wahl machine, each 60 of them consisting of two parts slidably connected together and controlled by a spring 102, tending to cause the two parts of the stop device to move toward each other so as to shorten the said device. The lower section of said stop device comprises a hook

103 adapted to catch under the lower flange of the dove-tail 68 and the other section comprises a similar hook adapted to catch over the upper dove-tail 68. Said upper section also comprises a tooth 104 adapted to engage spaces between the teeth 72 of the rack 73. These stop devices are so constructed that one of them can be located at any letter space position along the carriage 61 by catching the hook 103 under the lower dove-tail and stretching the device against the pressure of the spring 102 until the upper hook is caught over the upper dove-tail 68 when said spring will draw the tooth 104 into engagement with the rack 73. In Fig. 2 the totalizer is shown against the left-hand one of these stops 101, which thus defines the extreme left-hand position of said totalizer and another one of said stops is shown to define the extreme right-hand position of said totalizer. As was said above, these stops have heretofore been used on the Wahl machine. I have shown three stop devices 80 and two of the stops 101, the whole combination defining five adding columns. In practice five column stops 34 would be mounted on the column stop bar 35 in the rear of the machine in positions harmonizing with those of the stops 80 and 101. The operation of the machine is as follows:—The totalizer 70 is set against the left-hand stop 101 as shown in Fig. 2 and the tabulator is operated, bringing the typewriter and computer carriages into position to write a number in the first adding column and to add it on the totalizer. When this number has been written and registered, the appropriate one of the tabulator keys is again operated, causing the typewriter and computer carriages to move down to position for the next adding column. The operation of this key not only works the typewriter tabulator in the ordinary way but it also moves the depressing device 85 to its dotted line position, Fig. 2, with the result 110 that the left-hand one of the three stop devices moves under said depressor and has its pin 82 moved downward to position to control the manual setting of the totalizer. The operator does not instantly release the 115 tabulator key 25 but while holding it in its operated position manipulates the latch 71 and moves the totalizer 70 toward the right until it is arrested by the part 84 of the left-hand stop device. The operator then lets go of the latch 71 which is instantly moved to latching position under the impulse of the spring provided for the purpose. The operator then releases the tabulator key, allowing the depressor 85 to move back to its normal position and this also allows the pin 82 to be elevated to its normal position by its spring 83. The second number is then written and added in the ordinary way, 120 after which the tabulator is again operated, 125 130

causing the second pin 82 to move under and to be depressed by the depressor 85. The first pin 82 has by this time moved away from said depressor and is no longer 5 in the path of the totalizer. The operator can therefore, while maintaining pressure on the tabulator key 25, move the totalizer to the right until it is arrested by the second pin 82. The third number is then written, 10 after which the typewriter tabulator is again operated and the totalizer is again moved, this time until arrested by the third pin 82; the fourth number is then written after which the tabulator is again operated, 15 and the totalizer moved over against the right-hand stop 101, whereupon the last number in the list can be written and registered. The totalizer is then moved back toward the left past the stops 85 and against 20 the left-hand stop 101, the springs 83 which elevate said stops 84 being included in the means whereby this can be freely done. The carriage is returned to the right and the paper is line-spaced, whereupon the machine 25 is ready for writing another line of numbers and adding them into the register. Means are provided, including the depressor 85, whereby, in the course of the writing and adding of said line of numbers, the totalizer can be set back toward the right 30 against the stops, one after the other.

It will be perceived that I have provided very simple and easily added means for adapting the Wahl adding machine for 35 cross footing. It will also be readily understood that means working on the same principle can be applied to machines which in some respects differ quite widely from the Wahl machine. In a machine in which an 40 adjustable totalizer is mounted not on the carriage but on the stationary framework, the stop devices provided for guiding the setting of the totalizer would of course also be mounted on the stationary framework 45 and in case it was some other part of the computing machine than the totalizer that required to be adjusted, the corresponding changes would of course be made. Some of the devices shown are applicable to machines in which the re-adjustment or re-setting 50 of the settable part of the computing machine is done automatically. Various other changes can be made in the details of construction and arrangement without de- 55 parting from my invention.

What I claim as new and desire to secure by Letters Patent, is:—

1. The combination of a carriage, printing instrumentalities, computing mechanism including a part movable for denomination selection and adjustable by hand to different positions one for each of a plurality of different columns of figures, and a series of stops, one for each column, certain, 60 at least, of said stops being movable into

and out of position to control the manual adjustment of said part.

2. The combination of a carriage, a totalizer, a support along which said totalizer is adjustable to different positions one for 70 each column of numbers, means for securing said totalizer in each of said positions, and arresting devices for determining the adjustment of said totalizer, one arresting device for each of said column positions, certain, 75 at least, of said devices being movable into and out of arresting position.

3. The combination of a carriage, printing instrumentalities, an adjustable totalizer, stops each adjustable to different 80 column positions and each movable into and out of position to coöperate with said totalizer, and means for securing said totalizer in each of its column positions.

4. The combination of a carriage, printing instrumentalities, a manually adjustable totalizer, and arresting devices for determining a plurality of positions of said totalizer, certain, at least, of said arresting devices being movable temporarily and by an operation 90 separate from the manual adjustment of said totalizer into position to determine the manual adjustment of said totalizer.

5. In a combined typewriting and computing machine, devices for cross footing 95 comprising in combination with the carriage, the printing instrumentalities and the computing mechanism, said computing mechanism comprising a denomination selecting element connected to said carriage and capable of being set to different positions relative to said carriage, one or more stops for guiding the setting of said denomination selecting element of the computing mechanism, said stops being normally out 100 of the path of said element but movable into the path of it on occasion.

6. The combination with a carriage, printing instrumentalities, a totalizer, and master means, one of the last two recited parts 110 being adjustable to different column positions, of means for securing said adjustable part in the positions to which it is adjusted, and the stops 84 movable into and out of operative position, each of said stops 84 corresponding to one of said column positions.

7. The combination of a typewriting machine for writing numbers in a plurality of columns, computing mechanism including a part adjustable by hand to positions corresponding to different columns of figures, a series of stops, certain at least of said stops being movable into and out of position to control the manual adjustment of said part, and means for moving said stops into and 125 out of position to control the manual adjustment of said part, said means being controlled by a part of said typewriting machine that is operated at the time when said totalizer requires to be adjusted.

8. The combination of a carriage; printing instrumentalities; a tabulator; and computing mechanism including a part movable for denomination selection and settable by hand to different positions, one position for each of a plurality of different columns of figures, which columns of figures are located by said tabulator, and a series of stops each corresponding to one of said columns, certain at least of said stops being movable under the control of said tabulator into and out of position to control the manual adjustment of said part. 10
9. In a typewriting and computing machine, the combination of a carriage; printing instrumentalities for writing numbers in a plurality of columns; computing mechanism including a part settable to different positions corresponding to said columns; a bar; one or more stopping devices mounted on said bar; and means including a depressor for moving said stopping device or devices into and out of position to control the adjustment of said part. 15
10. In a machine of the character described, the combination of the carriage 61, the stop bar 74, the stop devices 80 adjustable along said bar and including movable stops 84, the depressor 85, and the means for operating said depressor. 20
11. In a machine of the character described, the combination of the typewriter carriage; the tabulator for controlling said carriage; the carriage 61; the stop bar 74; the stop devices 80 adjustable along said bar and including movable stops 84; the depressor 85; and means whereby said depressor is operated by said tabulator. 25
12. In a combined typewriting and computing machine, the combination of a carriage; printing instrumentalities; a tabulator including a series of tabulator keys; computing mechanism including a part adjustable by hand independently of the operation of said tabulator to different positions corresponding to different columns of figures written by said typewriting mechanism; and means controlled by said tabulator for guiding the manual adjustment of said part. 30
13. In a combined typewriting and computing machine, the combination of a carriage; printing instrumentalities; a tabulator including a series of tabulator keys; computing mechanism including a part traveling with said carriage and adjustable by hand to different positions corresponding to different columns of figures written by said typewriting mechanism; and devices traveling with said carriage and operable by any of said tabulator keys for controlling the manual adjustment of said part. 35
14. In a combined typewriting and computing machine, the combination of a typewriter carriage and printing instrumentalities capable of writing numbers in columns, a computer carriage traveling with said typewriter carriage, a totalizer adjustable on said computer carriage and capable in any of its positions thereon of partaking of the entire traverse of said computer carriage, and stops adjustable on said computer carriage and movable into and out of position to coöperate with said totalizer. 40
15. In a combined typewriting and computing machine, the combination of a typewriter carriage and printing instrumentalities capable of writing numbers in columns, a computer carriage traveling with said typewriter carriage, a totalizer adjustable on said computer carriage, stops adjustable on said computer carriage and movable into and out of position to coöperate with said totalizer, a tabulator, and means whereby said tabulator operates said stops. 45
16. The combination of a typewriter carriage, a computing mechanism including a part adjustable to different column positions to enable computations to be effected for a plurality of columns, a stop for arresting said adjustable part which stop is normally out of the path of said adjustable part so that the latter may be freely moved indefinitely from one column position to another, and means whereby said stop and said adjustable part may be relatively projected one into the path of the other to arrest the adjustable part at a predetermined position of adjustment. 50
17. The combination of a typewriter carriage, a totalizer, a support along which said totalizer is adjustable to different positions one for each of a plurality of different columns of numbers, a stop corresponding to one of said columns for arresting said totalizer and determining said adjustments, said stop being normally out of the path of said adjustable totalizer whereby the latter may be freely moved indefinitely along its support, and means whereby said stop may be projected into the path of said totalizer to arrest it at a predetermined position of adjustment. 55
18. The combination of a typewriter carriage, a totalizer, a support along which said totalizer is adjustable to positions corresponding to different columns of numbers, a stop for arresting said totalizer and determining said adjustments, said stop being adjustable to different letter space positions in order to vary the location of the column of numbers corresponding thereto, and said stop being normally out of the path of said adjustable totalizer whereby the latter may be freely moved indefinitely along its support, and means whereby said stop may be projected into the path of said totalizer to arrest it at a predetermined position of adjustment. 60
19. The combination of a typewriter car- 65

riage, a totalizer, a support along which said totalizer is adjustable to positions corresponding to different columns of numbers, a plurality of stops for arresting said totalizer and determining said adjustments, one such stop for each of said columns of numbers, said stops being normally out of the path of said adjustable totalizer whereby the latter may be freely moved indefinitely along its support, and means whereby any desired one of said stops may be projected into the path of said totalizer to arrest it at a predetermined position of adjustment.

20. The combination of a typewriter carriage, a totalizer, a support along which said totalizer is adjustable to positions corresponding to different columns of numbers, a series of stops for arresting said totalizer and determining said adjustments, one such stop for each of said columns of numbers, each of said stops being adjustable to different letter space positions in order to vary the location of the corresponding column of numbers, and said stops being normally out of the path of said adjustable totalizer whereby the latter may be freely moved indefinitely along its support, and means whereby any desired one of said stops may be projected into the path of said totalizer to arrest it at a predetermined position of adjustment.

21. In a combined typewriting and computing machine, the combination of a typewriter carriage and printing instrumentalities capable of writing numbers in columns, a computer carriage traveling with said typewriter carriage, a totalizer at all times adjustable on said computer carriage and stops adjustable on said computer carriage and normally out of the path of said carriage, and means for causing any desired one of said stops to arrest said totalizer in its adjusting movement.

22. In a combined typewriting and computing machine, the combination of a typewriter carriage and printing instrumentalities capable of writing numbers in columns, and a totalizer adjustable by hand to different column positions, stops for arresting

said totalizer when it is adjusted from one column position to another, and means whereby said totalizer can be either moved freely past any of said stops in the act of adjustment or can be caused to be arrested by one of said stops.

23. In a combined typewriting and computing machine, the combination of a carriage and printing instrumentalities capable of writing numbers in columns, a totalizer adjustable by hand to different column positions, stops for arresting said totalizer in the act of adjustment, and means whereby said totalizer can be moved past said stops toward the left, and can be set back against said stops toward the right.

24. In a combined typewriting and computing machine, the combination with typewriter mechanism capable of writing numbers in columns, of an adjustable totalizer, and a stop that is movable into and out of the path of the totalizer and against which said totalizer can be set by a separate act of manual adjustment.

25. In a combined typewriting and computing machine, the combination of a manually adjustable totalizer and a series of passable stops any one of which may be put into operative relation to the totalizer to arrest said totalizer when the latter is set by a separate manual adjustment thereof.

26. In a combined typewriting and computing machine, the combination with a carriage and tabulator stops, of a totalizer, a series of totalizer stops, and key-operated means for operating the tabulator stops and for simultaneously rendering operative one of said totalizer stops, said totalizer stops being rendered operative successively at successive operations of said key-operated means.

Signed at Paris, France, American consulate general, this 27th day of May, A. D. 1914.

RONALD McNAB.
